UNITED STATES PATENT OFFICE.

REUBEN C. BAKER, OF COALINGA, CALIFORNIA, ASSIGNEE TO BAKER CASING SHOE COMPANY, OF COALINGA, CALIFORNIA, A CORPORATION OF CALIFORNIA.

PITMAN END.

1,424,435.

Specification of Letters Patent. Patented Aug. 1, 1922.

Application filed April 21, 1920. Serial No. 375,422.

To all whom it may concern:

Be it known that I, REUBEN C. BAKER, a citizen of the United States, residing at Coalinga, in the county of Fresno and State of California, have invented a new and useful Improvement in Pitmen Ends; of which the following is a specification.

This invention relates to a well rig and particularly pertains to a bearing construction for walking beam pitmen.

Due to the fact that it is common practice to form pitmen of well rigs of wood, it is difficult to provide a suitable bearing for the crank pin to insure that excessive and objectionable wear will not take place.

It is the principal object of the present invention, therefore, to provide an adjustable bearing adapted to be readily operated to secure the crank pin and to permit the wear in the bearing to be easily taken up as it occurs and to furthermore provide simple means whereby the bearing may be instantly and easily separated to disengage the crank pin.

The present invention contemplates the use of a bearing structure adapted to be rigidly secured to the end of a pitman and to partially embrace a crank pin, said structure also providing guides for a supplemental movable bearing portion adapted to complete the circumscribing bearing for the crank pin and to be adjustably disposed in relation thereto.

The invention is illustrated by way of example in the accompanying drawings, in which:

Figure 1 is a fragmentary view in section and elevation showing the complete pitman structure with parts broken away to more clearly disclose the adjustable mechanism.

Fig. 2 is a view in central longitudinal section through the bearing and the pitman end.

Fig. 3 is a view in perspective showing one of the adjusting plates.

In the drawings 10 indicates a pitman adapted to be operatively connected to a crank pin 11. This pin is, in the present instance, surrounded by anti-friction bushings 12 and 13 which are made as a part of and solidly anchored to the bearing structure with which the present invention is particularly concerned. The bearing structure comprises a lower semi-circular bearing block 14 having a semi-circular recess therein to receive the bushing 12. This block is held in

position by a strap 15 which is drawn around the outer semi-circular contour of the bearing block 14 and is secured by bolts 16 to the pitman. The terminating ends of this strap are formed with inturned lugs 17 adapted to become embedded within the opposite sides of the pitman and thus to hold the straps against longitudinal movement. The bearing block 14 is also formed with a follower way 18. This way is bounded along opposite sides by vertical guides 19 and 20 which guides extend around the opposite edges of the recess in the bearing block and extend vertical and parallel. A follower block 21, which is fitted with bushing 13, is adapted to slide vertically between said guides in order to hold crank pin 11 in its operative position and form the upper half of the bearing. Outwardly extending longitudinal lugs 22 are formed along the opposite faces of block 21 and slide in slots 23 of the guides 19 and 20. By this expedient the follower block may move vertically without lateral movement in any direction. The guides are securely held against the end of the pitman by cap screws 24 which project into outwardly extending shoulders formed at the upper ends of the guides and which abut against the end of the pitman where it is cut to receive the pitman end and also by bolts 16 which secure the strap end to the pitman.

Positive vertical adjustment is provided the follower block. This construction comprises a pair of adjusting plates 25, adjusting blocks 26 and bolts 27. The adjusting plates 25 are more clearly shown in Fig. 3 where it will be seen that they have flat body portions adapted to rest upon the outer sides of the guides 19 and 20 and out-turned flanges 28. The upper faces of these flanges are outwardly and downwardly tapered to receive similar faces of the adjusting blocks 26. Longitudinal slots 29 are formed through the body plates of the members 25 and receive cap screws 30. These cap screws extend through the body plates and into the guide members 19 and 20 of the bearing block and are for the purpose of rigidly holding said adjusting plates 25 to their adjusted position actuated by adjusting blocks 26. These adjusting blocks 26 are flat on their upper faces to bear against the out-turned flanges of the guides and have tapered lower faces agreeing substantially with the taper of the 110

flanges 28. It will thus be seen that inward movement of the adjusting blocks 26 will cause the upper flat flanges and the lower tapered flanges to constitute a wedge and thus force down upon the flanges 28 of the adjusting plates 25 to produce positive adjustment. This inward movement of the adjusting blocks 26 is brought about by operation of adjusting screws 27 which, as shown in Fig. 1, are formed with an enlarged threaded portion passing through the adjusting blocks 26 which are threaded to receive them, and a reduced threaded portion passing through the strap 15. The outer end of this reduced portion is formed with a nut head so that by rotation of the screw the adjusting block may be moved in or out as desired, it being understood that the threads upon the reduced portions of these screws are not in engagement with any threads at the openings through which they pass, these threads being used only to receive lock nuts 28' by which the screws may be secured in their locked position and the adjusting blocks 26 thus held.

An instant release of the follower block 21 may be brought about by the lock bolt 30^a. This bolt has a cylindrical body portion at its opposite ends and an eccentric lock member 29 intermediate these ends. The lock member 29 is more clearly shown in Fig. 2 where it will be seen to operate within a transverse opening 30' through the follower block 21. The opposite cylindrical ends of the lock bolt 30^a extend through openings 31 in the adjusting plates 25 and thus the lock bolt 30^a will move simultaneously with the adjusting plates 25, in which the lock bolt has its bearings, when adjustment is being made. A crank 32 is secured upon one end of lock bolt and provides means by which this bolt may be rotated to raise the follower block 21 thereby releasing the crank pin 11.

In operation of the present invention the bearing block 14 may be securely bolted to the pitman with the follower block 21 between the guides 19 and 20 after which the babbitt bushings 12 and 13 may be renewed by repouring. Wear can be taken up or adjustment of the bearing made by loosening cap screws 30 and then rotating adjusting screws 27 to force the adjusting blocks 26 inwardly it being understood that at this time the lock bolt 30^a is in the position shown in Fig. 2. The inward movement of the blocks will, therefore, cause a wedging action against the flanges 28 of the adjusting plates 25 and will force these plates downwardly; in so doing the lock bolt 30^a will also be forced downwardly and will act upon the follower block 21 to force it firmly against the crank pin 11. When proper adjustment has been made the cap screws 30 are tightened to firmly hold adjusting plates 25 in their adjusted position and lock nuts 28' are

tightened to firmly hold the adjusting screws 27 and the adjusting blocks 26. In the event that the crank pin 11 is to be released the lock bolt 30^a is rotated by the crank 32. This action discontinues the pressure on and raises the follower block, thereby giving sufficient clearance to remove the bearing from the crank pin.

It will, therefore, be evident that by means of the present invention the bearing of the pitman end on the crank pin may be constantly tightened as required to prevent lost motion and consequential pounding and when desired the bearing may be instantly released to permit removal from or may be instantly tightened for engagement with the crank pin.

While I have shown the preferred form of my invention as now known to me, it will be understood that various changes in the construction, combination and arrangement of parts may be made by those skilled in the art without departing from the spirit of the invention as claimed.

Having thus described my invention, what I claim and desire to secure by Letters Patent, is:

1. A bearing structure comprising a bearing block having a bearing seat therein; guides extending from each side of said seat; a follower block slidably positioned between said guides and forming a bearing cap for the crank pin seat in the bearing block; a lock bolt journaled in the bearing block and having a cam portion extending within the follower adapted to retain the bearing cap and the bearing seat in a desired relative position or instantly separate them.

2. A bearing structure comprising a bearing adapted to be secured to the end of a pitman; a bearing seat formed therein for receiving a crank pin; guides formed on opposite sides of the seat; a follower block positioned between the guides and having a segmental end to form a cap for the bearing seat; wedge means for taking up the wear in the bearing; and a lock bolt journaled in the bearing and extending within the follower block for instantly separating the cap from the bearing seat.

3. A bearing structure comprising a bearing having a shaft receiving seat, guide members extending from opposite sides of said seat, a follower block slidably mounted between the guides and having a segmental end so as to form a cap for the bearing seat; wedge means for adjusting the cap in relation to the seat; a lock bolt journaled in the bearing and extending through the follower block, the portion extending within the follower block being cam-like for instantly bringing together or separating the cap and the bearing seat when the lock bolt is rotated.

4. A bearing for pitmen comprising a

semi-circular bearing block formed with a central seat for receiving a crank pin and provided with guide ways at the opposite side of said seat, means for securing said 5 block in position upon the end of a pitman, a follower block disposed between said guide ways and adapted to partially circumscribe a crank pin, adjusting blocks adapted to be operated to move the follower block against 10 the crank pin and lock means normally holding the follower block in its adjusted position and by which the follower block may be instantly released when desired.

5. In combination with a pitman rod, a 15 bearing structure adapted to be secured to the end thereof, and comprising a bearing

having a crank pin receiving seat, parallel guides extending from opposite sides of said seat, a follower block adapted to form a cap for the said seat, a cam-like bolt extending within the follower block adapted to adjust the relative position of the follower block 20 to the bearing, a strap secured to and embracing the bearing and having its extremities secured to the pitman.

In testimony whereof I have hereunto set my hand, in the presence of two subscribing witnesses.

REUBEN C. BAKER.
